Primary Examiner — Kelley A Donnelly(74) *Attorney, Agent, or Firm* — Craig R. Miles; CR MILES P.C.(57) **CLAIM**

We claim the ornamental design for a tray, as shown and described.

DESCRIPTION

FIG. 1 is a top perspective view of a tray, embodying our new design;

FIG. 2 is a bottom perspective view thereof;

FIG. 3 is a first side elevation view thereof;

FIG. 4 is a second side elevation view thereof;

FIG. 5 is a first end elevation view thereof;

FIG. 6 is a second end elevation view thereof;

FIG. 7 is a top view thereof; and,

FIG. 8 is a bottom view thereof.

1 Claim, 6 Drawing Sheets(56)
